UNITED STATES PATENT OFFICE.

THEOPHILUS VAN KANNEL, OF PHILADELPHIA, PENNSYLVANIA, ASSIGNOR
TO THE CANNERS' SUPPLY COMPANY, OF BRIDGETON, NEW JERSEY.

DESIGN FOR A TRAY.

SPECIFICATION forming part of Design No. 20,928, dated July 7, 1891.

Application filed June 13, 1891. Serial No. 396,194. Term of patent 7 years.

To all whom it may concern:

Be it known that I, THEOPHILUS VAN KANNEL, a citizen of the United States, and a resident of Philadelphia, Pennsylvania, have invented a Design for a Tray, of which the following is a specification.

My design for a tray is fully shown in the accompanying drawings, in which—

Figure 1 is a perspective view of the tray. Fig. 2 is a plan view of the same. Fig. 3 is an inverted plan view. Fig. 4 is a transverse section on the line 1 2, Fig. 2; and Fig. 5 is a longitudinal section on the line 3 4, Fig. 2.

The tray is oblong in contour and has an open bottom *a* and raised walls *b*, with outwardly-projecting flange *d* at the top. The sides of the tray are straight; but the ends of the tray are curved inward from each side toward the center, and these inwardly-curved portions meet, so as to form at each end of the tray an inwardly-projecting tapering tongue *f*, the flange *d*, however, being carried across the ends of the tray without following

these inward curves of the end walls, so that said flange is wider at the center of each end of the tray than at any other portion. As shown in Figs. 1, 2, and 3, the contour of the flange *d* at the ends of the tray is elliptical; but said flange may extend straight across the ends of the tray, as shown, for instance, by dotted lines in Fig. 2, without departing from the essential feature of the design, which is a tray having straight sides and incurved ends, forming the central inwardly-tapering tongues.

I therefore claim—

The design for a tray, substantially as described, and as shown in the accompanying drawings.

In testimony whereof I have signed my name to this specification in the presence of two subscribing witnesses.

THEOPHILUS VAN KANNEL.
